(57) **CLAIM**

The ornamental design for a tool holster, as shown and described.

DESCRIPTION

FIG. 1 is a perspective view of a tool holster according to our new design and being shown in an open position;

FIG. 2 is a front view thereof;

FIG. 3 is a rear view thereof;

FIG. 4 is a right-side view thereof;

FIG. 5 is a left-side view thereof;

FIG. 6 is a top plan view thereof;

FIG. 7 is a bottom plan view thereof;

FIG. 8 is a perspective view of a tool holster according to our new design and being shown in a closed position;

FIG. 9 is a front view thereof;

FIG. 10 is a rear view thereof;

FIG. 11 is a left-side view thereof;

FIG. 12 is a right-side view thereof;

FIG. 13 is a top plan view thereof; and,

FIG. 14 is a bottom plan view thereof.

Conventional shading is illustrated for purposes of highlighting the line drawings, but forms no part of the claimed design.

The dash-dash broken lines shown in FIGS. 1, 3, 4, 6, 8, 11, and 13 illustrate portions of the tool holster that form no part of the claimed design.

The dot-dash broken lines shown in FIGS. 1-4, 6, 8, 9, 10, 11, and 13 define the bounds of the claimed design and form no part thereof.
